UNITED STATES PATENT OFFICE

2,362,366

PULVERIZER ROTOR

John T. Fowler, Columbus, Ohio, assignor to The Jeffrey Manufacturing Company, a corporation of Ohio.

Application July 24, 1943, Serial No. 496,026

2 Claims.

(Cl. 83—11)

This invention relates to a pulverizer, and an object of the invention is to provide improved and simplified means for removably holding swing hammers, or the like, of a pulverizer in place and providing for their ready removal and renewal.

Other objects of the invention will appear hereinafter, the novel features and combinations being set forth in the appended claims.

In the accompanying drawing,

Fig. 1 is a sectional elevational view taken at right angles to the axis of rotation of the rotor of a pulverizer including the features of my invention;

Fig. 2 is an end view of the rotor of my invention, with the swing hammers omitted, the rotor shaft being shown in section;

Fig. 3 is a transverse sectional view through one end plate and one supporting disc of the rotor of Fig. 2;

Fig. 4 is a view similar to Fig. 2 of a modified form of my invention; and

Fig. 5 is a sectional view taken on the line 5—5 of Fig. 4, looking in the direction of the arrows, showing one end plate and one supporting disc of the rotor.

The general construction of the swing hammer pulverizer of my invention is disclosed in the patent to Walter J. Armstrong, No. 2,045,687, issued June 30, 1936, and unless a contrary fact is indicated, it is to be understood that the pulverizer follows the disclosure of said patent.

Briefly described, the pulverizer includes a main frame casing or housing 10 provided with a feed throat 11 and a reducing chamber 12, the bottom of the reducing chamber being formed by a bar screen 13. Within reducing chamber 12 is a rotor 14 which includes a rotor shaft 15 and a pair of end plates at opposite ends, one of which is seen at 16.

Also mounted on the shaft 15 between the end plates 16 is a plurality of supporting discs, one of which is seen at 17, said discs being spaced apart with reference to each other and with reference to the end plate 16 by spacers, one of which is seen at 18. The end plates 16, discs 17 and spacers 18 are all keyed to the shaft 15 and they have a press fit therewith. In addition, the rotor 14 includes four elongated tie bolts 19 which clamp the two end plates 16 together and thus hold said end plates 16, discs 17 and spacers 18 as a unitary structure on the shaft 15.

Extending through the two end plates 16 and each of the discs 17 and parallel with the axis

of the shaft 15 is a plurality of swing hammer supporting rods 20 upon which swing hammers 21 are pivotally mounted, said swing hammers extending between two successive discs 17 or, in some instances, between a disc 17 and an end plate 16.

In constructions heretofore made it has been difficult to remove the rods 20 for the purpose of reversing or renewing the swing hammers 21 and in addition the means for securing said rods 20 in place has not been in general very satisfactory. I have provided a novel construction which in one embodiment involves no removable small parts which can become lost, such as cotter keys or small screws, and in both embodiments of my invention I have provided simple mechanism which provides for the ready removal of the rods 20 while providing for their being securely maintained in place, once the parts are assembled.

Referring particularly to Figs. 2 and 3 of the drawing, it will be seen that each end plate 16 is provided with a peripheral groove 22 on its outside plane surface and this groove is adjacent the openings or holes through which the rods 20 extend. Within the groove 22 is a ring 23 which when fitted within the groove, substantially fills it, making its outer face preferably flush with the outer face of the end plate 16.

In one embodiment of the invention as illustrated in Figs. 2 and 3, the ring 23 is removably held in the groove 22 by spaced circular tabs 24 which are welded to the end plate 16 and have a portion thereof overlying the ring 23 in groove 22. The ring 23 is provided with spaced arcuate notches 25 to provide for its ready removal from the groove 22 which may be accomplished by adjusting the ring 23 until a notch 25 is adjacent the tab 24, whereupon said ring 23 can be removed.

The ring 23 is normally located in the position illustrated in Fig. 2 of the drawing, under which conditions said ring acts as an abutment for the ends of each of the rods 20. By releasing the locking mechanism, the ring 23 may be adjusted in the groove 22 so as to bring four holes 26 into alignment with four of the rods 20, whereupon said rods 20 may be removed.

The locking mechanism which I preferably employ, as illustrated in Fig. 2 of the drawing, includes a key 27 which is permanently attached to and rotatably mounted in a hole in the plate 16 and which is provided with a generally disc-like head 28 having a tool receiving slot 29 formed therein. Surrounding the head 28 is a

two-part ring having part 30 welded to the end plate 16 and part 31 welded to the ring 23, the said ring part 31 and the associated portion of ring 23 functionally operating as a recess in the ring 23. As a matter of fact, the structure illustrated might be made by forming an arcuate recess in the ring 23 positioned to receive the head 28.

It is evident that with the head 28 in said recess formed by the ring part 31, said ring 23 will be locked against rotary movement and thus will be held to operate as an abutment for one end of each of the rods 20.

The head 28 is provided with a removed or flattened portion 32 so that if the head 28 and key 27 are rotated, as by inserting a tool in the slot 29, so that the removed portion 32 is at the top as viewed in Figs. 2 and 3 of the drawing, the ring 23 will be free to rotate with respect to the end plate 16, and upon rotation thereof the holes 26 may be brought into alignment with the rods 20, providing for their ready removal.

In Figs. 4 and 5 of the drawing I have illustrated a modified type of mechanism for removably clamping the ring 23 to the end plate 16, which is simply a plurality of spaced screws 33 which extend through the ring 23 and are threaded into the end plate 16. Obviously by removing the screws 33, the ring 23 may be adjusted to bring selected openings or holes 26 into alignment with rods 20.

It is, of course, evident that when the rotor 14 is within the housing or casing 10, the ring 23 can not be removed, since the end plates 16 are closely adjacent the side walls of the casing or housing 10 and thus the rotary movement of the ring 23 with respect to the end plate 16 is desirable or necessary to permit removal of rods 20.

To gain access to the ring 23 and the locking mechanism, such as the key 27 and associated parts or the screws 33, each side of the housing 10 is provided with a removable door 34 which preferably extends from a horizontal plane passing through the axis of shaft 15 to a position above the top of rotor 14 as illustrated in Fig. 1 of the drawing.

From the above description of the device it is evident that in the assembled relation the parts will be in the positions illustrated in the drawing. If it is desired to reverse or renew or for any other reason remove one or more swing hammers 21, the two plates 34 on opposite sides of the housing or casing are first preferably removed. When this is done, a tool is inserted to rotate the key 27 and head 28, or remove the screws 33 in case the modification of Figs. 4 and 5 is involved. Assuming that the modification of Figs. 2 and 3 is involved, rotation of the key 27 and head 28 will be effected so that the removed portion 32 is adjacent the recess forming ring part 31. Under such conditions the ring 23 is free to rotate in the groove 22 and said ring 23 is rotated to align a plurality of openings 26 with a plurality of rods 20. This procedure may be followed with the rings 23 on opposite ends of the rotor 14. The ends of the plurality of rods 20 are thus exposed and by in-

serting a tool through openings 26 said rods 20 may be pushed out the side of the main frame or casing 10. By adjusting the rings 23 to align the different rods 20, it is possible to remove all 5 of said rods 20, if desired. Upon removal of the rods 20, the swing hammers 21 will be released for removal.

To reassemble the parts, swing hammers 21 will be held in position and rods 20 extended through aligned openings in the end plates 16 and discs 17 while the pivot holes on the swing hammers 21 are held in proper position. A reverse operation from that above described for disassembling the parts, will then be performed 15 to reassemble the complete rotor 14.

It is evident that with the parts assembled the rings 23 on opposite end plates 16 in both modifications of the invention, will act as abutments to hold said rods 20 in place.

It is to be noted that this assembly and disassembly of parts in either modification can be accomplished with only a screw driver, thus demonstrating the simplicity and ease of assembly and disassembly in the field.

Obviously those skilled in the art may make various changes in the details and arrangement of parts without departing from the spirit and scope of the invention as defined by the claims hereto appended, and I therefore wish not be restricted to the precise construction herein disclosed.

Having thus described and shown an embodiment of my invention, what I desire to secure by Letters Patent of the United States is:

35 1. A crusher rotor including end plates, a hammer supporting rod extending between said end plates and into an opening in at least one of said end plates, means removably holding said rod against outward movement relative to said 40 one end plate including a ring mounted thereon and having a hole spaced to be aligned with said rod, said ring being rotatably adjustable to bring said hole into alignment with said rod and also rotatably adjustable to present an abutment for 45 said rod, and means for holding said ring against rotation and on said end plate in rod abutting position, said means including a rotary locking key on said plate having a head adapted to extend into a recess in said ring when in one position of adjustment and having a removed portion adapted to provide for rotation of said ring when in another position.

2. A crusher rotor including an end plate, a rod extending through an opening in said end plate, an abutment ring mounted to rotate on said end plate, means holding said ring on said end plate while providing for its rotation to lock or release said rod, means for holding said ring against rotation and for releasing it for rotation, 55 said means including a rotary locking key mounted for turning in said end plate, said key having a disc-like head overlapping said ring extending into a recess in said ring when in locking position, said head having a removed portion adjustable opposite said recess when said ring is in a released position.

JOHN T. FOWLER.
